UNITED STATES PATENT OFFICE

2,318,900

PUNCH

Charles V. St. Louis, Oak Park, Ill., assignor to
 Wilson-Jones Company, Chicago, Ill., a corporation of Massachusetts

Application April 15, 1942, Serial No. 439,006

1 Claim. (Cl. 164—91)

This invention relates to a punch for perforating loose sheets of paper or similar material.

It is an object of this invention to provide a simple and inexpensive punch which will be positive in its operation. Other objects of this invention will become apparent upon reading the following description taken in conjunction with the accompanying drawings, in which:

Figure 1 is a sectional plan view of a punch embodying the invention;

Figure 2 is a detail perspective view of the punch plate;

Figure 3 is a detail perspective view of the plunger;

Figure 4 is a cross sectional view taken along the lines IV—IV of Figure 1;

Figure 5 is a detail perspective view of the punch handle;

Figure 6 is a cross sectional view taken along the lines VI—VI of Figure 4; and

Figure 7 is a cross sectional view taken along the lines VII—VII of Figure 4.

In the drawings, the reference numeral 2 indicates a base member provided with a pair of upstanding arms 3. The base member is shaped to form a chip receptacle and is provided with a sliding closure member 4. The base member is also provided with a sliding side gauge 5 secured thereto in any suitable manner. In the preferred embodiment the entire punch base is formed of molded plastic material, and a metal punch plate 6 is secured to the base member by means of the rivets 7. The punch plate is provided with a pair of apertures 8 adapted to cooperate with the punch pin 9 in the punching operation. It will be understood that in the event the punch base is made of metal instead of plastic material, the punch plate may be dispensed with.

Each arm 3 is apertured, as indicated at 10, to receive a punch pin 9. The upper portion of the

aperture 10 is enlarged, as indicated at 11, to form a shoulder 12 upon which a coiled spring 13 is seated. The upper portion of the arms 3 are apertured to receive a rod 14. The handle 15 is provided with a shaft 16, which is provided with an eccentrically spaced aperture 17 mounted on the rod 14.

A pair of plungers 18, each of which is provided with a collar 19 fitting snugly over the ends 10 of the shaft 16, are each apertured, as indicated at 20, to receive the upper end of the punch pins 9. The punch pins 9 are secured in the apertures 20 by means of pins 21.

When the handle 15 is depressed the eccentric shaft 16 forces the plungers 18 downwardly, and these plungers 18 carry the punch pins with them. When the handle is released the coiled springs 13 force the plungers 18, and the punch pins 9, upwardly to clear the throat 22 of the punch.

Although I have described one embodiment of my invention in detail, it will be understood that the description thereof is illustrative, rather than restrictive, as many details may be modified or changed without departing from the spirit or scope of the invention. Accordingly, I do not desire to be restricted to the exact details of construction described, except as limited by the appended claim.

I claim:

30 In a punch, a pair of upstanding arms each apertured to receive one end of a punch pin, an eccentric shaft mounted on said arms, a pair of plungers mounted on said shaft, said plungers each having an aperture adapted to receive the 35 other end of one of said punch pins, and a coiled spring inserted with each of said punch pins, said springs having their opposite ends positioned in said apertures.

CHARLES V. ST. LOUIS.
